UNITED STATES PATENT OFFICE

KAROL P. RYBAK, OF TAYLOR, PENNSYLVANIA

CURTAIN BRACKET

Application filed May 1, 1930. Serial No. 448,953.

This invention relates to windows and the like and has special reference to curtain and shade supports for windows. One important object of the invention is to provide an improved general construction of devices of this character.

A second important object of the invention is to provide an improved curtain and window shade bracket adapted to be clamped onto the window frame.

A third important object of the invention is to provide a novel arrangement of folding bracket for this purpose.

A fourth important object of the invention is to provide novel means on a folding bracket of this character for carrying the curtain rod supports in a detachable and adjustable manner.

A fifth important object of the invention is to provide a novel form of adjustable clamp for such a device.

A sixth important object is to provide a novel shade roller attachment for such brackets.

With the above and other objects in view, the invention consists in general of certain novel details of construction and combinations of parts hereinafter more fully described, illustrated in the accompanying drawings and specifically claimed.

In the accompanying drawings like characters of reference indicate like parts in the several views, and:

Figure 1 is an elevation of the top portion of a window frame for a double window showing the improved brackets applied to the top member of such frame;

Figure 2 is an enlarged elevation of the center bracket removed from the frame and with the curtain rod holders detached;

Figure 3 is a view of the parts shown in Figure 2 but from the opposite or rear side thereof;

Figure 4 is an enlarged section on the line 4-4 of Figure 3;

Figure 5 is an enlarged section on the line 5-5 of Figure 3;

Figure 6 is an enlarged section on the line 6-6 of Figure 3;

Figure 7 is an enlarged section on the line 7-7 of Figure 3;

Figure 8 is a rear face view, partly in section of a shade roller support used herewith.

Figure 9 is a plan view, partly broken away, of the shade roller support;

Figure 10 is a view similar to Figure 1 but showing a modification of the device adapted to be clamped to the vertical members of the window frame;

Figure 11 is an elevation of one of the side brackets arranged as in Figure 10 but with the curtain rod supports removed;

Figure 12 is a rear elevation of the parts shown in Figure 11;

Figure 13 is an enlarged section on the line 13-13 of Figure 12;

Figure 14 is an enlarged section on the line 14-14 of Figure 12;

Figure 15 is an enlarged section on the line 15-15 of Figure 12;

Figure 16 is an enlarged detail front elevation of another form of adjustable clamping jaw;

Figure 17 is a plan view of the jaw shown in Figure 16;

Figure 18 is a plan view of the jaw shown in Figure 10;

Figure 19 is a front elevation of the jaw shown in Fig. 18;

Figure 20 is a front view of a curtain rod support for use herewith;

Figure 21 is an end view of this rod support;

Figure 22 is a rear view of this rod support;

Figure 23 is a perspective view of a modified form of curtain rod support.

In each form of bracket here shown there is provided an elongated body member 10 having its top and bottom edges bevelled as at 11 on its rear face. Projecting upwardly from each body 10 is a pair of arms 12 which carry at their upper ends a channel member 13 opening forwardly and having the confronting faces of its flanges undercut to provide bevels 14. These channels carry the detachable curtain rod supports as will be presently described. The double bracket used in the center of a double window and in other

- similar places has two of these body members connected by a hinge joint 15. Each single bracket has, in place of this hinge joint, a rearwardly projecting flange 16 wherethrough extends a clamping screw 17 having a toothed clamping jaw 18 swivelled on its inner end. Each body 10 also has an elongated keyhole slot formed therein, said slot extending from a circular portion 19 about central of the length of the body longitudinally of said body away from the clamp or hinge and having a straight portion 20 terminating in an upwardly inclined extremity 21.
- 15 In the form shown in Figure 1, there is provided a clamp having a rearwardly facing channel body 22 from which extends a lateral lug 23 carrying a button 24 so proportioned that this button may be entered through the opening 19 and slid along the slot 20 with the clamp at right angles to the body 10. At its upper end this clamp is provided with a rearwardly extending flange 25 wherethrough extends a clamp screw 26 having on its lower end a serrated clamping jaw 27. Slidable in the lower portion of the channel 22 is a clamping jaw having a body 28 fitting the channel and a rearwardly projecting toothed flange 29 at its lower end.
- 20 The body 28 is slotted as at 30 and one side of the slot is provided with ratchet teeth 31 which face downwardly and are engaged by a spring pressed pawl 32 pivoted in the channel 22. By this means a rapid adjustment for length of this clamp may be made through movement of this sliding jaw while the full clamping power may be applied by the screw 26.
- 25 In the form of the invention shown in Figure 10, there is provided a clamp, the body 40 of which as shown in detail in Figs. 18 and 19, is simply a flat plate having a rearwardly projecting flange forming a jaw 41 and being provided with the button 42 and lug 43 as before described. This clamping member is not in itself adjustable and may be termed a fixedly positioned clamping jaw although it is detachable because its operative position is fixed.
- 30 In the form of clamp shown in Figures 16 and 17, the clamp embodies a channel body 33. A button 34 is arranged on the back of this body and is used to connect the clamp to the body as before, but there is also provided a lug 35 which, when the clamp is on the body 10, fits in the angle portion 21 of the slot to hold this clamp aligned with the body 10. A flange 36 is provided at one end of the channel and a clamp screw 37 extends through this flange and carries a jaw 38 formed by a rearwardly projecting flange on a slide 39 working in the channel 33. With this type of jaw, adjustment may be had at each end of the bracket.
- 35 The curtain rod supports of Figures 20 to

22 consist each of a flat plate 44 having forwardly projecting rod hooks 45 and a longitudinally extending undercut rib 46 on its back fitting slidably into the channel 13. On one of the arms 12 is pivoted a latch lever 47 urged upwardly by a spring 48 and carrying a lug 49 which passes through an opening in the bottom of the channel 13 and enters a notch 50 in the bottom of the rib 46 to hold the curtain rod support in position.

75 In the form shown in Figure 23, used for supporting the centers of long rods, there is provided a bevelled plate 51 having a notch 52 in its lower edge for the lug 49 and provided with a forwardly projecting rod supporting hook 53.

80 Each shade roller support consists of a body 54 from which projects a small bracket 55 of the usual form. A bevelled flange 56 projects rearwardly from the lower edge of this body and through this flange extends a stem 57 carrying at its upper end a plate 58 having a complementary bevelled flange 59. The plate 58 is slidably mounted on the body and the flange 59 is urged toward the flange 56 by a spring 60 surrounding the stem 57 and supported by a nut 61.

85 By means of this construction the clamps may be readily applied to the window frame and will hold the devices firmly in position as shown in Figures 1 and 10.

90 There has thus been provided a simple and efficient device of the kind described and for the purpose specified.

95 It is obvious that changes may be made in the form and construction of the invention without departing from the principles thereof. It is not, therefore, desired to confine the invention to the exact form herein shown and described but it is desired to include all such as come within the scope claimed.

100 I claim:

105 In a device of the kind described, a body, clamping means carried by the body for securing the body to a fixed object, a channel member carried by the body, a curtain rod bracket carrying plate slidably engaged in said channel member and a spring pressed latch lever pivoted to the body member and provided with a latch lug entering the channel of the channel member, said plate having a lug receiving notch in which said lug engages to hold the plate immovable with respect to said channel member.

110 In testimony whereof I affix my signature.

115 KAROL P. RYBAK.
